UNITED STATES PATENT OFFICE.

ARCHIBALD F. REDDIE, OF PHILADELPHIA, PENNSYLVANIA, ASSIGNOR TO
WILLIAM H. McCALLUM AND IRVING McCALLUM.

DESIGN FOR CARPET.

SPECIFICATION forming part of Design No. 24,619, dated August 20, 1895.

Application filed July 12, 1895. Serial No. 555,788. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for Carpet or other Fabric, of which the following, taken in connection with the accompanying drawing, is a specification.

The design illustrated in the accompanying drawing may be wrought in or applied to Brussels, Wilton, velvet, or other carpet, and in such colors or combinations of colors as may be desired.

In the drawing, *a* is the body, *b* the border, and *a b* the carpet, and the drawing clearly shows the peculiar characteristic or distinctive appearance which when imparted to the carpet or other fabric constitutes my invention.

The leading or characteristic feature or fea-

tures of my design may be said to be the group of roses *c*, the single roses *d*, the rosebuds *e*, and the trailing vines *f*, displayed upon a background *g* and in the drawing associated with *h* bands or stripes *h* and *i*.

What I claim as new, and desire to secure by Letters Patent, is—

1. In the design for carpet the body *a*, substantially as shown. 30
2. In a design for carpet the border *b*, substantially as shown.
3. The design for carpet consisting of the body *a*, and the border *b*, substantially as shown. 35

In testimony whereof I have hereunto signed my name.

ARCHIBALD F. REDDIE.

Witnesses:

ANNA K. MAY,
HARRY O. SWEARER.
